UNITED STATES PATENT OFFICE.

FRED E. ASELTINE, OF DAYTON, OHIO, ASSIGNOR TO GENERAL MOTORS RESEARCH CORPORATION, OF DAYTON, OHIO, A CORPORATION OF DELAWARE.

INTAKE MANIFOLD.

Application filed May 26, 1923. Serial No. 641,623.

To all whom it may concern:

Be it known that I, FRED E. ASELTINE, a citizen of the United States of America, residing at Dayton, county of Montgomery, 5 and State of Ohio, have invented certain new and useful Improvements in Intake Manifolds, of which the following is a full, clear, and exact description.

This invention relates to improvements 10 in fuel mixture supply for internal combustion engines and particularly to intake manifolds.

It is among the objects of the present invention to obtain maximum fuel economy at 15 part engine load and to obtain maximum power at full load.

The present invention provides apparatus 20 for supplying heat to the fuel mixture flowing into the engine for facilitating the vaporization of the liquid fuel, and for controlling this heat supply in such a manner that the mixture is heated until it is desirable to obtain a maximum volumetric efficiency.

25 Further objects and advantages of the present invention will be apparent from the following description, reference being had to the accompanying drawing wherein a preferred embodiment of the present invention is clearly shown.

In the drawings:

Fig. 1 is a front elevation of an intake and exhaust manifold including a carburetor.

35 Fig. 2 is a sectional view taken along the line 2—2 of Fig. 1.

Fig. 3 is a sectional view taken along the line 3—3 of Fig. 1.

Referring to the drawings the numeral 40 20 designates the exhaust manifold of the engine which comprises a plurality of branch conduits 21 in communication with the main conduit 22, the latter being in communication with the exhaust pipe 23 which 45 leads to atmosphere or a muffler not shown on the drawings. The main exhaust conduit 22 is provided with a flat surface 24 in which is formed an elongated continuous channel 25.

50 The intake manifold 26 comprises a main fuel mixture conduit 27 and a plurality of branch conduits 28 and 29 communicating with the main fuel mixture conduit 27. The outer ends of these branch conduits 28 and 55 29 communicate with engine intake ports

represented by the dotted circles 30 and 31 respectively. A plate 32 conforming in size and shape to the size and shape of the flat surface of the exhaust manifold 22 is formed integral with the intake conduit 27, 60 said plate 32 also being provided with an elongated continuous channel 33 which, when the exhaust and intake manifolds are in position on the engine will align with the channel 25 formed in the exhaust conduit 22 65 to provide the channel 34 termed the bypass hereinafter. The plate 32 is provided with a plurality of lugs 35 having holes adapted to receive bolts 36 which screw into the exhaust conduit 22, thus holding the 70 plate 32 in engagement with the exhaust conduit 22. The entire exhaust and intake manifold assembly is held on the engine by means of straps 38 and bolts 39, the latter screwing into the engine block not shown 75 on the drawings.

The main fuel mixture conduit 27 is provided with a flange 40 to which a similar flange 41 formed on the carburetor 42 is 80 adapted to be secured for supporting said carburetor in position on the intake manifold. The means for controlling the engine operation comprises a throttle valve 43 mounted on a rod 44 which projects through the carburetor passage to the outside thereof, one end of said rod having a lever 45 secured thereto by means of which the throttle 43 may be manually adjusted. The opposite end of the rod 44 carries an operating arm 46 whose function will be described 90 hereinafter.

The conduit 27 is in communication with the bypass 34 by means of the passage way 47 which may be termed the entrance passage. The branch conduits 28 and 29 of 95 the intake manifold are in communication with the bypass 34 by means of the pipe connections or exit passages 48 and 49 respectively.

As may be seen on the drawings, the pipe 100 48 connects with the branch manifold conduit near its engine intake port 30, while the opposite end of the pipe 48 connects with the upper portion of the bypass 34, substantially midway between the outer end thereof and the main intake conduit 27. This is also true in regard to the pipe 49 and its branch conduit 29.

The means for shunting the fuel mixture 110 through the heated conduit or bypass 34

comprises a control valve 50 carried by the rod 51 which is journalled in the sides of the conduit 27, one end of said rod projecting on the outside of said conduit and supporting the operating element 52 which comprises a hub portion 53 having a projection 54 formed thereon which carries the weight block 55. A downwardly projecting shifter fork is provided on the hub 53, said fork comprising a left prong 56 and a right prong 57. The control valve 50 is positioned in the conduit 27 above the entrance passage 47. A stop 58 is formed on the outside of the conduit 27 which is adapted to engage either the left prong 56 or the right prong 57 to hold the control valve either in passage closing or opening position respectively.

When the throttle valve 43 is substantially in passage closing position, the arm 46 associated with the said valve is adapted to engage the prong 57 in such a manner as to hold the operating element 52 in such a position where the control valve 50 will close the passage way in the conduit 27. Upon operation of the lever 45, by the operator, to open the throttle valve 43, the arm 46 will be moved in a counterclockwise direction, said arm after having been operated through a predetermined portion of its range will engage with the prong 56 and upon continued operation or opening of the throttle 43, the arm 46 will move the prong 56 to the left rotating the hub 53 in a clockwise direction and when the weight block 55 has passed the vertical line through the axis of the hub, said weight block will quickly move the operating element 52 to the position where the prong 57 will engage with the stop 58. In this position the control valve 50 will be in the conduit opening position.

When the engine is idling, that is, when the throttle valve 43 is in a position to very nearly shut off the passage way in the carburetor, the arm 46 will, as has been mentioned heretofore, hold the operating element 52 in a position where its associated control valve 50 is in closed position. This will cause the fuel mixture flowing from the carburetor to pass through the entrance passage 47 and enter the by-pass 34 which, after the engine has been operated for a short time, will become heated, due to the fact that this by-pass lies adjacent the main exhaust conduit 22. After having passed through the by-pass 34, the heated gas or fuel will flow through either of the pipe connections 48 and 49, into the branch conduits 28 or 29 respectively depending upon the operation of the engine. In order to obtain maximum fuel economy at part engine loads, or while the throttle is in such a position that the passage in which said throttle is positioned, is partially closed,

the fuel mixture is directed through the heated by-pass during a certain portion of the range of engine operation.

Referring to Fig. 1, it may be seen that the control valve 50 will remain in the conduit closing position as is shown in dotted lines until the throttle 43 has been moved to cause the arm 46 to engage with the left prong 56 of the operating member 52, causing said operating member to be rotated in a clockwise direction until the weight block 55 has passed through the central vertical axis of the hub, at which time said weight block will operate the valve 50 very quickly to open the passage way through this conduit. This will continue the flow of fuel mixture through the passage way 47 into the heater by-pass 34, the fuel mixture then being directly carried through the conduit 27 to the various branch conduits 28 and 29 and thence to the combustion chambers of the engine. In this position, the maximum volumetric efficiency of the engine is obtainable and the throttle has still a certain range of operation to entirely open the passage of the carburetor in which it is positioned.

From the foregoing it may be seen that fuel mixture flowing through the conduit 27 will be shunted through the by-pass 34 to the branch conduit 28 and 29 during a certain portion of the range of throttle operation or until the element 52 has been shifted to open the control valve 50 when the fuel will flow directly through the conduit 27 to the branch conduits 28 and 29. The former range, or more specifically the range of throttle operation from the substantially closed position to the position where the control valve 50 is opened, is greater than the remaining portion of the range, that is to such a position where the throttle is entirely open and reversely the range of of throttle operation from the full open position to the position where the control valve 50 is operated to close the conduit 27, is greater than the remaining throttle range from the latter point to where said throttle is again substantially closed. It will be seen that after the use of the heater by-pass has been discontinued the range of throttle operation to obtain maximum power at substantially full load is substantially increased.

During the initial operation, and particularly before the exhaust manifold has heated up the by-pass 34 to such a degree where vaporization will be facilitated, the liquid or moist particles of the fuel mixture passing through the conduit 27 into the entrance passage 47 and thence into the by-pass 34, will tend to gather in the bottom of the upper portion of the by-pass. As the by-pass becomes heated from continued engine operation, these moist particles of fuel will tend to evaporate within the space of said by-pass 34, between the points where the

pipes 48 and 49 communicate therewith, the vapor then being drawn into either one of the said pipes 48 or 49 depending upon the operation of the engine.

5. It will of course be understood that fuel mixture passing to the left through the bypass 34 will primarily pass into the pipe 48 and thence into the conduit branch 28. However, fuel mixture remaining in the 10 upper portion of this left hand side of the by-pass may be drawn through the pipe 49 into the branch conduit 29 when its associate pistons are on the suction stroke.

15 While the form of embodiment of the invention as herein shown and described constitutes a preferred form, it is to be understood that other forms might be adopted, all coming within the scope of the claims which follow.

20 What I claim is as follows:

1. In an internal-combustion engine a fuel supply device, including an intake manifold having a main fuel supply passage, and a shunt passage; a heating means for heating 25 the shunt passage; an engine throttle; and a device controlled by the throttle for instantly, fully closing the main passage at a predetermined point in the closing movement of the throttle and for instantly, fully 30 opening the main passage at a corresponding point in the opening movement of the throttle.

2. A fuel supply device for an internal-combustion engine including an exhaust 35 manifold comprising, in combination, an intake manifold including a main fuel mixture passage and a by-pass adapted to be heated by the exhaust manifold; a communicating channel leading from the main conduit to the by-pass; a carburetor connected to the intake manifold; a pair of normally closed valves in the main fuel passage having the communicating channel interposed therebetween; means for operating one of the valves 40 through its range of travel; means for holding the other valve immovable for a predetermined portion of the travel of the first valve, to control the flow of mixture through one passage, and for causing the quick shifting 45 of the second valve through its entire range of operation when the first valve starts on its remaining range of travel, to direct the course of the fuel mixture flow through another passage.

55 3. In a fuel supply device, the combination with an internal-combustion engine and means for controlling engine operation; of an intake manifold including a conduit adapted to be heated by the engine and including a comparatively cooler conduit; means controlled by the engine controlling means for shunting all the fuel mixture through the heated conduit while the engine operation controlling means is being operated through a portion of its range of

travel and for directing all the fuel mixture through the cooler conduit while said engine controlling means is being operated through its remaining range of travel.

4. A fuel supply device for an internal-combustion engine comprising, in combination, an intake manifold including an engine heated conduit and a comparatively cooler conduit; a carburetor connected to the manifold; a throttle valve therefor; and means connected with the throttle valve for shunting all the fuel mixture through the heated conduit while the throttle valve is being operated through the portion of its range of travel; and for directing all the fuel mixture through the cooler conduit while said throttle is being operated through the remaining portion of its range of travel.

5. A fuel supply device for an internal-combustion engine comprising, in combination, an exhaust manifold; an intake manifold including a comparatively cool, main conduit and a by-pass heated by the exhaust manifold; a carburetor connected to the manifold; a throttle valve in said carburetor; a control valve in the main conduit of the manifold, normally in conduit closing position to cause all the fuel mixture to pass through the heated by-pass; means for operating the throttle, including means to operate the control valve out of normal to full-open position after the throttle has been operated through a portion of its range of travel, whereby to cause all the fuel mixture to flow through the main conduit to the engine, for the remaining portion of the range of throttle travel.

6. A fuel supply device for an internal-combustion engine comprising, in combination, an exhaust manifold; an intake manifold including a comparatively cool, main conduit and a by-pass heated by the exhaust manifold; a carburetor connected to the manifold; a throttle valve in said carburetor; a control valve in the main conduit of the manifold, normally in conduit closing position to cause all the fuel mixture to pass through the heated by-pass; means for operating the throttle, including means to operate automatically the control valve out of normal to full-open position after the throttle has been operated through a portion of its range of travel, whereby to cause all the fuel mixture to flow through the main conduit to the engine; for the remaining portion of the range of throttle travel.

7. A fuel supply device for an internal-combustion engine comprising, in combination, an exhaust manifold; an intake manifold including a comparatively cool, main conduit and a by-pass heated by the exhaust manifold; a carburetor connected to the manifold; a throttle valve in said carburetor; a control valve in the main conduit of the manifold, normally in conduit closing

- position to cause all the fuel mixture to pass through the heated by-pass; means normally adapted to hold the control valve in normal conduit closing position; and means 5 for operating the throttle including means to move the control valve holding means out of normal position, which means will automatically move the control valve to conduit opening position after the throttle has been 10 moved through a portion of its range of travel thereby to permit the fuel mixture to flow through the main conduit during the remaining portion of the range of throttle travel.
- 15 8. A fuel supply device for an internal-combustion engine comprising, in combination, an exhaust manifold; an intake manifold including a comparatively cool, main conduit and a by-pass heated by the exhaust 20 manifold; a carburetor connected to the manifold; a throttle valve in said carburetor; a control valve in the main conduit of the manifold and having a normal, conduit closing position for causing all of the fuel 25 mixture to flow through the heated by-pass, and having a conduit open position for permitting all the fuel mixture to flow through the main conduit to the engine; controlling means normally adapted to hold the control 30 valve in either one of its positions but capable of moving said valve; and means for operating the throttle, including means adapted to move the control valve controlling means out of its normal valve holding 35 position after the throttle has been operated through a portion of its range of travel whereby said controlling means will operate the valve from one to the other of its positions to control the flow of fuel mixture.
- 40 9. A fuel supply device for an internal-combustion engine comprising, in combination, an exhaust manifold; an intake manifold including a comparatively cool, main conduit and a by-pass heated by the exhaust 45 manifold; a carburetor connected to the manifold; a throttle valve in said carburetor; a control valve in the main conduit of the manifold and having a normal, conduit closing position for causing all of the fuel 50 mixture to flow through the heated by-pass, and having a conduit open position for permitting all the fuel mixture to flow through the main conduit to the engine; weighted 55 means normally adapted to hold the control valve in either one of its positions but operable by gravity to quickly move said valve from one position to the other; and means for operating the throttle including means adapted to engage with and move the weighted means out of its normal valve holding position after the throttle has been 60 operated through a portion of its range of travel whereby said weighted means will quickly move the valves from one to the other of its positions.
- 65 10. A fuel supply device for an internal-combustion engine comprising, in combination, an exhaust manifold; an intake manifold including a comparatively cool, main conduit and a by-pass heated by the exhaust 70 manifold; a carburetor connected to the manifold; a throttle valve in said carburetor; a control valve in the main conduit of the manifold and having a normal, conduit closing position for causing all of the fuel 75 mixture to flow through the heated by-pass, and having a conduit open position for permitting all the fuel mixture to flow through the main conduit to the engine; weighted 80 means normally adapted to hold the control valve in either one of its positions but operable by gravity to quickly move said valve from one position to the other; and means for operating the throttle including an arm adapted to engage with the weighted means 85 to hold it in its valve holding position while the throttle is being moved through a portion of its range of travel and adapted to move the weighted means out of its normal valve holding position and cause said means 90 to shift the valve position when the throttle has completed this portion of its range of travel, said arm holding the weighted means in this second valve holding position while the throttle is being operated through its remaining portion of travel range.
- 95 In testimony whereof I hereto affix my signature.

FRED E. ASELTINE.
